(57) **CLAIM**

The ornamental design for a dry mobile device camera case, as shown and described.

DESCRIPTION

FIG. 1 is a front view of the dry mobile device camera case in the closed position;

FIG. 2 is a rear view of the dry mobile device camera case in the closed position;

FIG. 3 is a rear view of the mobile device in the dry mobile device camera case in the closed position;

FIG. 4 is a top view of the dry mobile device camera case in the closed position;

FIG. 5 is a bottom view of the dry mobile device camera case in the closed position;

FIG. 6 is a left view of the dry mobile device camera case in the closed position;

FIG. 7 is a right view of the dry mobile device camera case in the closed position;

FIG. 8 is a front view of the dry mobile device camera case in the closed position with the latch unclasped;

FIG. 9 is a left view of the dry mobile device camera case in the closed position with the latch unclasped;

FIG. 10 is an external view of the dry mobile device camera case in the open position with the latch unclasped;

FIG. 11 is an internal view of the dry mobile device camera case in the open position with the latch unclasped;

FIG. 12 is a left view of the dry mobile device camera case in the open position with the latch unclasped; and,

FIG. 13 is an internal view of the mobile device in the dry mobile device camera case in the open position with the latch unclasped.
